UNITED STATES PATENT OFFICE.

JOHN PLAYER, OF DUNKIRK, NEW YORK, ASSIGNOR TO THE BROOKS LOCOMOTIVE WORKS, OF SAME PLACE.

RADIAL TRUCK.

SPECIFICATION forming part of Letters Patent No. 673,727, dated May 7, 1901.

Application filed March 5, 1901. Serial No. 49,987. (No model.)

To all whom it may concern:

Be it known that I, JOHN PLAYER, of Dunkirk, in the county of Chautauqua and State of New York, have invented a certain new 5 and useful Improvement in Radial Trucks, of which improvement the following is a specification.

My invention relates to so-called "radial trucks" for locomotive-engines and other rail- 10 road rolling-stock in which lateral motion or radial movement of a bearing-axle of the vehicle relatively to the main frame thereof is provided for to facilitate and reduce strains in the passage of the vehicle into, through, 15 and from curved portions of the track.

The object of my invention is to provide effective and desirable means whereby an increased range of lateral movement in the axle may be permitted, the construction of the 20 axle-box guides and their connection to the main frame simplified and cheapened, and improved facilities provided for transmitting the weight carried by the springs to the radial axle and equalizing it with that borne by 25 the adjacent driving-axle.

The improvement claimed is hereinafter fully set forth.

In the accompanying drawings, Figure 1 is a side view in elevation of a radial trailing- 30 wheel truck for locomotive-engines, illustrating an embodiment of my invention, the trailing wheel nearer the observer being shown in dotted lines; Fig. 2, a plan or top view of the same; Fig. 3, a vertical transverse section at 35 the line *a* *a* of Fig. 2, and Fig. 4 a front view in elevation with the engine frame and springs in transverse section.

My invention is herein shown as applied in a trailing truck employed to support the rear 40 portions of the main-frame bars 1 of a locomotive-engine and the weight which is carried thereon. The trailing wheels 2 are secured in the usual manner upon the outer ends of the truck-axle 3, the journals 4 of 45 which rotate in journal-bearings 5, set in axle-boxes 6, each of which is fitted with the capacity of relative lateral as well as vertical movement between a pair of pedestals 7. The front and rear sides of the axle-boxes 6 are 50 curved concentrically upon radii struck from a center located at a proper distance forward

of the truck-axle in the longitudinal central plane of the engine, and the opposite axle-boxes are connected by an upper horizontal plate 8 and vertical front and rear plates 9, 55 which are preferably, as shown, cast integral with the axle-boxes. The continuous structure thus formed may descriptively be termed the "axle-box frame." The inner faces of the pedestals 7 are curved correspondingly 60 with the axle-boxes, and the members of each pair of pedestals are connected at their lower ends by pedestal tie-bolts 10, which pass through thimbles or spacing-pieces 11, interposed between the pedestals, and are provided with nuts 12, by which they are drawn to the proper bearing. Each of the pedestals forms the outer end portion of an axle-box guide, which is composed of two pedestals on opposite sides of the engine and an intermediate connecting-plate 13, cast integral therewith, and each pedestal is provided at its top with an upwardly-extending lug or flange 14, which abuts against the inner side of the adjacent main-frame bar 1 and is secured thereto by bolts or rivets 15. This construction obviates the necessity of forging separate pedestals or horn-plates upon the main-frame bars, thereby effecting a material structural simplification and economy and, 70 moreover, permitting increase of lateral or radial movement, as desired, by simply reducing the length of the axle-box guides. 75

In order to control the lateral movements of the axle-box frame in passing curves and 80 return it to and maintain it in its normal central position on tangents, a centering-spring 85 16 is provided, said spring being illustrated as inclosed in a spring-box 17, fixed to the lower sides of the vertical plates 9 of the axle-box frame, with its ends abutting against followers 18, which in turn abut against shoulders on the ends of the spring-box. Two thrust-rods 19, the outer ends of which are fixed to members connected with the main-frame bars 1, abut at their inner ends against the followers 18, the distance between the inner ends of the followers being equal to the maximum amount of traverse of the axle-box frame and axle on either side of the central 90 plane of the engine. In the instance shown the thrust-rods 19 are connected at their outer 100

ends to the thimbles 11 of the follower tie-bolts 10 by nuts 20, by the adjustment of which the distance between the inner ends of the thrust-rods may be increased or diminished, 5 as desired, so as to thereby increase or diminish, respectively, the degree of lateral traverse permitted to the axle-box frame. Under the above construction it will be seen that the centering-spring will be compressed by lateral 10 movement of the axle-box frame in either direction and will return the same to normal central position as the compression is released by the opposite movement of the axle-box frame, thereby preventing jars or shocks and 15 reducing liability to strain in the movements of said frame.

The specific location of the centering-spring relatively to the axle-box frame is not an essential of my invention, and it may, if preferred, 20 be located on the top or on the sides of the axle-box frame, as may be found most convenient in different forms of construction of the radial truck. It will also be obvious that the relative positions of the centering-spring 25 and thrust-rods may be changed without departure from the spirit of my invention—that is to say, centering-springs may be attached to the pedestals or other parts which are fixed to the frame members and thrust-rods acting 30 thereon attached to the axle-box frame.

The weight carried upon the truck-axle 3 is in the instance shown transmitted thereto through two semi-elliptical springs 21, the 35 rear ends of which are coupled by spring-hangers 22 to the main-frame bars 1 and the forward ends of which are coupled by spring-hangers 23 to equalizers 24. The equalizers 24 are pivoted by bolts 25 to the main-frame bars and are coupled at their forward ends to 40 the springs of the rear pair of driving-wheels in the ordinary or any preferred manner. The spring-bands 26 rest upon a carrying-bar 27, the ends of which may, as shown, be turned upwardly, and form thrust-blocks bearing 45 against chafing-plates or rubbing-castings 28, fixed to the inner sides of the main-frame bars 1 and interposed between the same and the spring-bands 26. The under side of the carrying-bar is a true surface, which rests upon 50 the top of the axle-box frame, to which the weight carried by it and by the truck axle and wheels is transmitted by the springs in such manner as to permit its lateral movements to be effected without interference with the position or action of the springs.

The carrying-springs may, if preferred, be underhung or located below the axle-box frame instead of above it, as shown, and for use in connection with a leading truck a single 60 transverse spring or system of coiled springs may be employed instead of the two longitudinal springs shown. When so placed, the spring is connected centrally with an equalizer and rests at its ends upon a carrying-bar, such as above described, or, equivalently, 65 upon two short sections thereof, each of

which bears, in the manner described, upon the top of the axle-box frame.

My improvement has been applied in practice in the construction of a number of locomotive-engines and has in regular service been found to successfully attain the objects for which it was designed. The employment of trailing wheels for the support of wide and deep fire-boxes has in recent practice been 75 very generally approved and adopted by railroad-managers, and my invention enables their application to be desirably effected, by reason of its capability, generally, of promoting the safe and easy passage of the engine 80 through curves and also of the fact that its spring arrangement is one which will not interfere with the sloping ash-pans which are used with wide fire-boxes. The construction is free from complication or undue expense 85 and is particularly suited to the requirements of American practice.

I claim as my invention and desire to secure by Letters Patent—

1. In a radial truck, the combination of a 90 main frame, two transverse axle-box guides secured thereto, an axle-box frame fitted to traverse between said guides, an axle journaled therein, a centering-spring supported on the axle-box frame, followers abutting 95 against the opposite ends of said spring, thrust-rods, each abutting at its inner end against one of the followers and connected, at its outer end, to the axle-box guides, and means for varying and adjusting the distance 100 between the inner ends of the thrust-rods.

2. In a radial truck, the combination of a main frame, two transverse axle-box guides having end pedestals secured thereto, an axle-box frame fitted to traverse between said 105 guides, an axle journaled therein, pedestal tie members connecting the two pedestals on each side of the frame, a centering-spring supported on the axle-box frame, followers abutting against the opposite ends of said spring, 110 thrust-rods, each abutting, at its inner end, against one of the followers, and nuts engaging screw-threads on the thrust-rods and connecting the same adjustably to the pedestal tie members.

3. In a radial truck, the combination of a main frame, two transverse axle-box guides, each having an integral end pedestal and an upwardly-extending lug or flange abutting against and secured to the adjacent main-frame member, an axle-box frame fitted to traverse between the pedestals of said guides, and an axle journaled in said axle-box frame.

4. In a radial truck, the combination of a main frame, two transverse axle-box guides 125 secured thereto, an axle-box frame fitted to traverse between said guides, an axle journaled therein, a transverse carrying-bar, the under surface of which rests and bears truly 130 upon the axle-box frame, and a spring bearing upon the carrying-bar and transmitting weight to the truck-axle through said bar.

5. In a radial truck, the combination of a main frame, two transverse axle-box guides secured thereto, an axle-box frame fitted to traverse between said guides, an axle journaled therein, a transverse carrying-bar, the under surface of which rests and bears truly on the axle-box frame, a spring bearing upon the carrying-bar, and an equalizer coupled to the main frame and to said spring.
10. In a radial truck, the combination of a main frame, two transverse axle-box guides secured thereto, an axle-box frame fitted to traverse between said guides, an axle journaled therein, a transverse carrying-bar, the under surface of which rests and bears truly on the axle-box frame, and having end-thrust blocks bearing on the main-frame members, and a spring bearing on the carrying-bar and transmitting weight to the truck-axle through said bar.
15. In a radial truck, the combination of a main frame, two transverse axle-box guides secured thereto, an axle-box frame fitted to traverse between said guides, an axle journaled therein, a transverse carrying-bar, the under surface of which rests and bears truly on the axle-box frame, and having end-thrust blocks bearing on the main-frame members, and springs coupled at their ends to the main-frame members and bearing intermediately upon the carrying-bar.
20. In a radial truck, the combination of a main frame, two transverse axle-box guides secured thereto, an axle-box frame fitted to traverse between said guides, an axle journaled therein, a transverse carrying-bar, the under surface of which rests and bears truly on the axle-box frame and which is provided with end-thrust blocks, chafing-plates interposed between and abutting against the thrust-blocks and the main-frame members, and a spring bearing on the carrying-bar and transmitting weight to the truck-axle through said bar.
25. In a radial truck, the combination of a main frame, two transverse axle-box guides secured thereto, an axle-box frame fitted to traverse between said guides, an axle journaled therein, a transverse carrying-bar, the under surface of which rests and bears truly on the axle-box frame, and having end-thrust blocks bearing on the main-frame members, springs, bearing intermediately of their ends upon the carrying-bar, equalizers pivoted to the main-frame members and coupled to the springs, and connections coupling the opposite ends of the springs to the main-frame members.
30. In a radial truck, the combination of a main frame, two transverse axle-box guides secured thereto, an axle-box frame fitted to traverse between said guides, an axle journaled therein, a transverse carrying-bar, the under surface of which rests and bears truly on the axle-box frame and which is provided with end-thrust blocks, chafing-plates interposed between and abutting against the thrust-blocks and the main-frame members, and a spring bearing on the carrying-bar and transmitting weight to the truck-axle through said bar.
35. In a radial truck, the combination of a main frame, two transverse axle-box guides secured thereto, an axle-box frame fitted to traverse between said guides, an axle journaled therein, a transverse carrying-bar, the under surface of which rests and bears truly on the axle-box frame and which is provided with end-thrust blocks, chafing-plates interposed between and abutting against the thrust-blocks and the main-frame members, and a spring bearing on the carrying-bar and transmitting weight to the truck-axle through said bar.
40. In a radial truck, the combination of a main frame, two transverse axle-box guides secured thereto, an axle-box frame fitted to traverse between said guides, an axle journaled therein, a transverse carrying-bar, the under surface of which rests and bears truly on the axle-box frame, and having end-thrust blocks bearing on the main-frame members, springs, bearing intermediately of their ends upon the carrying-bar, equalizers pivoted to the main-frame members and coupled to the springs, and connections coupling the opposite ends of the springs to the main-frame members.
45. In a radial truck, the combination of a main frame, two transverse axle-box guides secured thereto, an axle-box frame fitted to traverse between said guides, an axle journaled therein, a transverse carrying-bar, the under surface of which rests and bears truly on the axle-box frame, and having end-thrust blocks bearing on the main-frame members, springs, bearing intermediately of their ends upon the carrying-bar, equalizers pivoted to the main-frame members and coupled to the springs, and connections coupling the opposite ends of the springs to the main-frame members.
50. In a radial truck, the combination of a main frame, two transverse axle-box guides secured thereto, an axle-box frame fitted to traverse between said guides, an axle journaled therein, a transverse carrying-bar, the under surface of which rests and bears truly on the axle-box frame, and having end-thrust blocks bearing on the main-frame members, springs, bearing intermediately of their ends upon the carrying-bar, equalizers pivoted to the main-frame members and coupled to the springs, and connections coupling the opposite ends of the springs to the main-frame members.
55. In a radial truck, the combination of a main frame, two transverse axle-box guides secured thereto, an axle-box frame fitted to traverse between said guides, an axle journaled therein, a transverse carrying-bar, the under surface of which rests and bears truly on the axle-box frame, and having end-thrust blocks bearing on the main-frame members, springs, bearing intermediately of their ends upon the carrying-bar, equalizers pivoted to the main-frame members and coupled to the springs, and connections coupling the opposite ends of the springs to the main-frame members.

JOHN PLAYER.
